UNITED STATES PATENT OFFICE.

RUTHERFORD H. BOWSHER, OF ADELPHI, OHIO.

ARTIFICIAL TOOTH.

1,223,364.

Specification of Letters Patent. Patented Apr. 24, 1917.

Original application filed June 5, 1916, Serial No. 101,790. Divided and this application filed February 13, 1917. Serial No. 148,337.

To all whom it may concern:

Be it known that I, RUTHERFORD H. BOWSHER, a citizen of the United States, residing at Adelphi, in the county of Ross and 5 State of Ohio, have invented certain new and useful Improvements in Artificial Teeth, of which the following is a specification.

This invention has relation to useful improvements in artificial teeth and especially 10 to the structure and construction thereof and it embodies the novel features described fully hereinafter.

This application is a division of application No. 101,790.

15 The main object of my invention is to provide means for reinforcing an artificial tooth, which means are fully concealed behind the body of the tooth and are securely connected therewith in such manner that 20 said tooth will not become displaced with relation to said reinforcing means.

A further object of the invention is to provide in connection with said reinforcing means, a portion, integral therewith, adapted to extend, at a suitable angle, from the outer end thereof, inwardly, which portion forms the grinding portion of said tooth.

A still further object of the invention is to provide specific means for connecting the 30 brace with the tooth so that the latter may be freely utilized and will effectually withstand whatever strains that may be placed thereupon, while in use.

Another object of the invention is to provide a tooth of such character and construction that will be especially adapted for fitting the same in an artificial bridge, however, before the latter is secured permanently in position.

40 With the foregoing and other objects in view, my invention consists of the novel features of construction, combination and arrangement of parts, as are described in this specification, illustrated in the accompanying drawings forming a part thereof and particularly pointed out in the claim hereunto appended.

Reference being had to the drawings:

Figure 1 is a perspective view of the reinforcing means together with said grinding portion integral therewith, extending at a suitable angle therefrom, as hereinbefore indicated.

Fig. 2 is a vertical sectional view of my 55 improved tooth, the reinforcing means and

said portion thereof, above-mentioned, being illustrated in side elevation.

Referring more particularly to the drawings, my invention is described as follows:

The reinforcing means employed in conjunction with the tooth 1, hereinafter referred to as a tooth facing 1, which may be composed of porcelain or any other material adaptable for the purpose, consists of a bracing plate 2, which is substantially flat, 60 the outer end portion thereof being bent outwardly at a required angle in conformity with the outer end of said tooth facing 1.

A portion of the reinforcing means extends at substantially right angles to that 70 portion thereof, specifically indicated, hereinbefore, as a bracing plate 2 and at the outer end thereof, being integral therewith. The said portion, or, as commonly known in dentistry, cusps 3, present a grinding surface which cooperates with the grinding surface of the oppositely disposed tooth upon the opposite jaw.

Extending from the outer face of the bracing plate 2, at a suitable acute angle toward its inner end, is a pin 4, integral therewith which corresponds to and is received by a bore 5 formed in the tooth facing 1 from the inner face thereof. Said bore extends into the tooth facing 1 at an obtuse 80 angle toward its inner end, the same being filled with cement before the pin 4 is placed thereinto. A second bore 6 communicates with the first-mentioned bore each at its inner end and arranged at an obtuse angle to each other, said last-mentioned bore or escape vent 6 being for the express purpose of carrying off the excess or surplus cement that may be present in the first-mentioned bore 5, during the insertion of said 90 pin into the latter. The bore 6 terminates and expels the excess cement, if any, at the inner end of the tooth 1.

Although I have specifically described the 100 novel features of construction, combination and arrangement of the several parts of my invention, yet I do not confine myself to same but reserve and may exercise the right to make such changes therein as do not depart from the spirit of the invention or the 105 scope of the appended claim.

What I claim as new, is:

A tooth provided with a facing having a bore extending thereinto at an acute angle 110 toward its inner end, a second bore commu-

nicipating with the first-mentioned bore at the inner end of each, said second bore extending into said facing from the inner end thereof and forming with the first-mentioned bore an obtuse angle, reinforcing means comprising a backing plate, a pin protruding from the outer face thereof, which pin is normally received by and held in the first-mentioned bore, a portion of said

reinforcing means being bent inwardly at a 10 suitable angle to the backing plate thereof to form the cusps of the tooth.

In testimony whereof I affix my signature in the presence of two witnesses.

RUTHERFORD H. BOWSHER.

Witnesses:

R. R. DUFFIE,

RUDOLPH T. HARRELL.
